PRIMER FOR PUMPS AND THE LIKE

Filed May 18, 1945

UNITED STATES PATENT OFFICE

2,483,019

PRIMER FOR PUMPS AND THE LIKE

Daniel Murphy, New Castle, Pa.

Application May 18, 1945, Serial No. 594,546

9 Claims. (Cl. 103—113)

1

My invention relates to pumps for liquid, particularly to rotary or centrifugal liquid pumps, and consists in certain new and useful improvements in self-priming means for such pumps.

In Letters Patent of the United States No. 2,179,858, granted on my application November 14, 1939, I illustrate and describe a rotary pump provided with means for preventing the pump while at rest from becoming "gas bound" and for automatically priming the pump when it is set in operation. In the pump of such prior patent the inlet passageway of the pump extends from the supply of liquid being pumped upward to a point above the impeller chamber of the pump, and this passageway includes a check valve, to prevent back drainage or syphonage of the liquid from the pump to the supply of liquid when pump operation is interrupted. The outlet passageway of the pump extends upward from the pump, and in keeping with the invention disclosed in such patent a by-pass is provided from the outlet passageway to the inlet passageway, the by-pass opening in the inlet passageway at a point between the impeller chamber and the check valve. This by-pass is effective, when the pump is shut down, to permit the gas accumulating in the inlet passageway on the pump side of the check valve to be vented into the outlet passageway of the pump, and it is also effective to provide for a back flow of liquid from the outlet passageway into the inlet passageway of the pump, with the effect that the pump does not become gas bound. Furthermore, an adequate body of liquid is provided in the impeller chamber and inlet passageway of the pump to establish proper operation when the pump is set in motion.

The by-pass between the inlet and outlet passageways of the pump of my earlier patent was formed with relatively small diameter, and this sometimes resulted in the by-pass becoming clogged in service. Indeed, a feature of the structural organization of my prior patent consisted in the provision of a removal access element, whereby the by-pass could be readily cleaned either when the pump was in operation or when it was at rest. My present invention is based on the provision of a non-clog port or by-pass between the inlet and outlet passageways of a pump, and the invention consists in certain new and useful improvements in structure and structural organization which are effective not only to eliminate this problem of the clogging by-pass, but additionally to provide for the regulation of pump capacity or output while the rotor or impeller of the pump is operated at normal or optimum speed.

2

The invention will be understood upon reference to the accompanying drawings, in which:

Figure 1 is a view partly in vertical section and partly in side elevation of a pump priming device embodying my present invention. The device may be integrally embodied in a pump structure, or it may be constructed as a unit to be assembled with a pump, as the need may arise in meeting particular demands of industry;

10 Figure 2 is a view in side elevation of a certain control lever of the priming device; and

Figure 3 is a view to smaller scale of a rotary pump of the type described in my said earlier patent. The pump herein is shown partly in side elevation and partly in axial section, and is intended merely to exemplify one of the many pumps with which, or in which, the priming device of my present invention may be used.

Referring first to Figure 3 of the drawings, the 20 exemplary pump will be understood to comprise a pump body 1 and a cover plate 2, forming an involute pump chamber 4 of usual type. A shaft 5 supports a vaneed impeller 6 in the chamber 4, and within a cylindrical body portion 1a of 25 the pump the shaft is supported by a bearing which is described in Letters Patent No. 2,128,496, granted to me August 30, 1938. The shaft is coupled to the shaft of an electric motor, or other drive (not shown). When the pump is in 30 operation the liquid to be pumped is by the rotating impeller drawn through the pump inlet 7 into the impeller chamber, and is delivered through an outlet 8, the arrows a and b respectively illustrating the inflow and delivery of the 35 liquid being pumped.

In accordance with my present invention, I provide (as mentioned above) a non-clog port between the inlet and outlet passageways of the pump. This port opens into the outlet passageway 40 from the inlet passageway at a point above the impeller chamber and between the usual check valve and the impeller chamber of the pump. Organized with this port is a shutter, or the like, which is arranged to keep the port entirely closed 45 during pump operation at normal or most efficient speed. Means are provided for shifting the shutter and opening the port to required degree when it is desired to start the pump after a period of idleness, with the effect that any accumulated 50 gas in the inlet passageway is vented into the outlet passageway of the pump, and a backflow of liquid from the outlet to the inlet passageway primes the pump for immediate operation. In further accordance with the invention the shutter is arranged to be secured with the port un-

covered a greater or less degree while the pump is in operation, whereby there is a regulated recirculating flow from the outlet to the inlet passageway of the pump. Thus, while the pump is operated at the speed productive of greatest efficiency (either from the standpoint of the power requirements of the pump drive, or of the pressure of the liquid delivered), the output or rate of delivery of the pump may be regulated. As already noted, this improved structural organization may be integrally incorporated in the pump structure per se, or it may be provided as a primer unit to be assembled with any desired pump. In this case, I show the structure as such a unit.

Considering Figure 1, the primer unit consists in a body 10 including inlet and outlet passageways 11 and 12, enlarged in their extent to form respectively a primer chamber 13 and an outlet chamber 14, separated by a wall or partition 15 that includes the non-clog port 16. The unit is provided with a flange 43 arranged to be bolted to the flange 44 of the pump, to secure the unit to the pump, with the inlet passageway 11 in communication with the inlet 7 of the pump and the passageway 12 connected to the outlet 8 of the pump. This organization will be understood even though the pump is shown on much smaller scale than the primer unit. It will also be understood that the primer unit may be installed at an interval above the pump, with pipes of suitable size connecting the passages 11 and 12 of the primer unit with inlet and outlet 7 and 8, respectively, of the pump.

The inlet passageway 11 is connected to the pipe 31, or other intake, leading from the supply of liquid to be pumped, and a delivery pipe 33 leads outward or upward from the outlet passageway 12. As usual, a check valve 32 is organized in the line of flow from the supply of liquid to the impeller chamber, and in this case the check valve is provided in an independent housing 30 connected between the intake pipe 31 and the inlet passageway of the primer unit.

A shutter 17, or other suitable device, is arranged normally to close the port 16, and in order to insure tight closure the port is bushed with a bronze seat 18, while the shutter is provided with a facing 19 of rubber, preferably a synthetic rubber such as neoprene. The shutter is carried by a rod 20, which extends outward through a packing gland 21 on the wall of the housing 10, and a spring 22, compressed between a collar 23 on the shaft and a bracket 24 rigid with the housing structure, yieldingly secures the shutter in seated position. The shaft 20 extends beyond the bracket 24 and is equipped with a handle 25, and a dial 26 is provided on the bracket, as shown, for purposes presently to be described.

In normal pump operation the port 16 is closed, and the liquid being pumped is drawn upward through the intake 31 and check valve 32, and then inward and downward through the primer chamber 13 into the impeller chamber 4 of the pump. Under the influence of the rapidly rotating impeller 6 the liquid is delivered from the pump through outlet 8, outlet chamber 14 and delivery pipe 33.

When the operation of the pump is interrupted, the flow of fluid stops, and the check valve 32 closes. The delivery pipe 33, outlet chamber 14, passageways 12 and 8, impeller chamber 4, inlet passageways 7 and 11, and primer chamber 13 are filled with liquid, and under such conditions the pump may, manifestly, be started up without priming. However, it is found that when a pump

is allowed to stand idle for a substantial interval of time an air or gas pocket forms in the intake passageways between the check valve and impeller chamber of the pump, whereby, when the pump is started up the air or gas prevents the development of adequate suction to draw liquid upward in the intake 31. The pump is said to be "gas bound."

In overcoming this objection in the pump of the present invention, the handle 25 is pulled outward (to the left in Figure 1) and turned before, or when, the pump is started up. This moves the shutter 17 from position in which it closes the port 16, and in consequence the air or gas entrapped in the inlet passageways of the pump is vented, under the effect of its inherent buoyancy, through the port 16 and into the outlet chamber 14 and delivery pipe 33, while liquid from the latter chamber and pipe flows through the port 16 to take the place of the vented gas. Accordingly, the pump may be placed in operation at normal speed, which is the speed that affords most efficient operation of the pump, as mentioned above.

After the pump has been set in operation, the port 16 is reclosed, if maximum output of the pump is desired. But if it be desired to operate the pump at less than maximum output, with the pump operating at normal speed, the shutter is allowed to remain positioned with the port 16 uncovered, in consequence of which there is a recirculation of the pumped liquid from the outlet chamber to the primer chamber. The output of the pump is reduced by the amount of the 35 recirculation. The index or dial 26 on the end of the bracket 24 may be calibrated as shown in Figure 2, and thus the position of the handle 25 may be used to indicate the position of the shutter 17, to provide any desired output between a predetermined maximum and minimum.

Several additional features are to be noted of the device of this invention. It will be observed that the primer chamber 13 is formed to provide a substantial space for containing liquid below the point at which liquid enters such chamber from the check valve, wherefore, if the check valve should happen to leak when the pump is shut down, the back syphonage of water through the pipe 31 cannot prevent a self-priming operation of the pump, since in the lower portion of the primer chamber 13 there will always be an adequate quantity of liquid for the purpose.

A baffle 27 extends transversely of the primer chamber 13, and this baffle faces the by-pass or port 16 and is spaced at an interval therefrom. Incidentally, an observation and cleanout port is provided above the baffle and is normally closed by a plug 27. It will be noted that the baffle obstructs direct flow between the port 16 and the upper portion of the passage 11 leading from the check valve 32. The baffle extends downward such distance that its lower edge will lie below the surface of the body of water contained in the lower half of the primer chamber 13 when the pump is at rest, while the upper edge of the baffle stops short of the top of chamber 13. Thus, when the shutter 17 is opened to vent trapped gas, the gas in the inlet passageway leading from the check valve is free to flow over the upper edge of the baffle and enter the port 16, while the fluid surging back through the port from the outlet passages strikes the baffle and flows beneath the lower edge thereof, that is, if the pump is not in operation at the time. If the pump should be 70 in operation the back-surfing liquid enters the

intake of the pump, and establishes conditions that bring the pump into normal operation without the necessity of priming.

The baffle is also valuable when the pump is operating continuously at less than maximum capacity, that is, with the shutter in partially or fully open position. Under such circumstances the liquid recirculating or flowing back through the port 16 strikes the baffle and is deflected downwardly, to enter the pump inlet 1 in a stream paralleling the stream entering the pump by way of the check valve. This feature is of importance in the provision of a variable output self-priming pump structure.

Within the spirit of the invention defined in the appended claims, many modifications and variations are permissible.

I claim as my invention:

1. In a centrifugal pump having a pumping chamber with a rotary pumping member therein, an inlet passageway including a check valve at a point above said chamber, an outlet passageway leading from said chamber, a partition between said passageways, said partition including a non-clog priming port opening into said outlet passageway from said inlet passageway at a point between said check valve and said pumping chamber, a shutter organized with said port, and means extending inwardly through the wall of said outlet passageway for securing said shutter in various flow-controlling positions with respect to said port, whereby the output of the pump operating at normal speed may be regulated.

2. A unit for attachment to a rotary pump having an inlet and an outlet, said unit including a body having inlet and outlet passageways extending therethrough for connection severally to said inlet and outlet of the pump, a non-clog port between said passageways in said unit, and an upwardly extending baffle arranged in the line of flow through said inlet passageway, said baffle being spaced from and extending transversely of said port and providing adjacent to its top and bottom for flow from one side of the baffle to the other, with provisions for the flow of liquid and gas around the baffle.

3. A unit for attachment to a rotary pump having an inlet and an outlet, said unit including a body having inlet and outlet passageways extending therethrough for connection severally to said inlet and outlet of the pump, a non-clog port between said passageways in said unit, and a baffle arranged in the line of flow through said inlet passageway, said baffle being spaced from and extending transversely of said port, a clearance for the passage of gas adjacent to the top of said baffle, and a clearance for the flow of liquid adjacent to the bottom of said baffle.

4. A unit for attachment to a rotary pump having an inlet and an outlet, said unit including a body having inlet and outlet passageways extending therethrough for connection severally to said inlet and outlet of the pump, a non-clog port between said passageways in said unit, and a baffle arranged in the line of flow through said inlet passageway, said baffle being spaced from and extending transversely of said port, a clearance for the passage of gas adjacent to the top of said baffle, and a clearance for the flow of liquid adjacent to the bottom of said baffle, a shutter for said port, and means for moving said shutter between positions in which said port is closed and open.

5. In combination with a pump having a pumping chamber provided with an inlet passageway

extending from a point above said chamber downwardly thereto and including a check valve above said chamber, and an outlet passageway extending upwardly from said chamber; a priming device comprising a priming chamber in said inlet passageway, a non-clog port between said priming chamber and said outlet passageway, an upwardly extending baffle in said priming chamber arranged in spaced relation with respect to said port and having clearances for flow adjacent to its top and bottom, a shutter for said port, and means for moving said shutter from port-closing position into a position in which gas accumulating in said chamber when the pump is at rest may be vented into said outlet passageway and liquid from the latter passageway may be introduced to said priming chamber.

6. In combination with a pump having a pumping chamber provided with an inlet passageway extending from a point above said chamber downwardly thereto and including a check valve above said chamber, and an outlet passageway extending upwardly from said chamber; a priming device comprising a priming chamber in said inlet passageway, a non-clog port between said priming chamber and said outlet passageway, a baffle extending transversely of said priming chamber and arranged in spaced relation with respect to said port, a passage for the flow of gas adjacent to the top of said baffle, a passage for the flow of liquid adjacent to the bottom of said baffle, a shutter for said port, and means for moving said shutter from port-closing position into a position in which gas accumulating in said chamber when the pump is at rest may be vented into said outlet passageway and liquid from the latter passageway may be introduced to said priming chamber.

7. For combination with a pump having walls forming a pumping chamber provided with an inlet and an outlet passageway extending upwardly from the pumping chamber, a priming device having a priming chamber arranged above said pump inlet and communicating therewith, said priming chamber having an inlet passage with a check valve, a partition between said priming chamber and said outlet passageway, a non-clog port in said partition, a shutter for said port, and means extending inwardly through the wall of said outlet passageway for moving said shutter from port-closing into open position in which gas in said priming chamber is vented into said outlet passageway and liquid from the latter passageway is introduced to said priming chamber for priming the pump when it is set in operation.

8. For combination with a pump having walls forming a pumping chamber provided with an inlet and an outlet passageway extending upwardly from the pumping chamber, a priming device having a priming chamber arranged above said pump inlet and communicating therewith, said priming chamber having an inlet passage with a check valve, a partition between said priming chamber and said outlet passageway, a non-clog port in said partition, a shutter for said port, and means extending inwardly through the wall of said outlet passageway for moving said shutter from port-closing into open position in which gas in said priming chamber is vented into said outlet passageway and liquid from the latter passageway is introduced to said priming chamber for priming the pump when it is set in operation.

9. A unit for attachment to a rotary pump

having an inlet and an outlet, said unit including a body having inlet and outlet passageways extending therethrough for connection severally to said inlet and outlet of the pump, a non-clog port between the passageways in said unit, an upwardly extending baffle spaced from said port and arranged in the line of flow through said inlet passageway, transverse passages adjacent to the top and to the bottom of said baffle, a shutter for said port, and means for adjusting said shutter in various port-controlling positions, whereby the output of the pump operating at normal speed may be regulated.
